(57) **CLAIM**

The ornamental design for an aspirator side bracket, as shown and described.

DESCRIPTION

FIG. 1 is a perspective view showing our new design;

FIG. 2 is a front elevation view thereof;

FIG. 3 is a left side elevation view thereof;

FIG. 4 is a rear elevation view thereof;

FIG. 5 is a top plan view thereof;

FIG. 6 is a right side elevation view thereof; and,

FIG. 7 is a bottom plan view thereof.

The broken line representations of a foundation portion of the pump, jar, valves, tubing, gauges, dials and fittings in FIGS. 1-7 do not limit the claimed design.

The broken line showing of foundation portion of the pump, jar, valves, tubing, gauges, dials and fittings in FIGS. 1-7 are included for the purpose of illustrating and forms no part of the claimed design.
